UNITED STATES PATENT OFFICE.

JAMES H. BULLARD, OF SPRINGFIELD, MASSACHUSETTS.

TENNIS-COURT MARKER.

SPECIFICATION forming part of Letters Patent No. 339,141, dated April 6, 1886.

Application filed September 21, 1885. Serial No. 177,639. (No model.)

To all whom it may concern:

Be it known that I, JAMES H. BULLARD, a citizen of the United States, residing at Springfield, in the county of Hampden and State of Massachusetts, have invented new and useful Improvements in Tennis-Court Markers, of which the following is a specification.

This invention relates to improvements in lawn-tennis-court markers, the object being to provide a marker for laying out a tennis-court of improved construction, whereby by rolling the marker on the court-lines the marking material is deposited on the latter, and at the same time the proper length of the lines is measured by the revolutions of the marker.

In the drawings forming part of this specification, Figure 1 is a perspective view of a lawn-tennis-court marker embodying my improvements, the upper end of the handle thereof being broken off. Fig. 2 illustrates a modified construction of the marker-cylinder, as hereinafter described.

In the drawings, A is the marker wheel or cylinder, consisting of two metallic sides, *c c*, of suitable sheet metal, preferably sheet-tin, the peripheries of which are provided with serrations, as shown in Fig. 1, or made plain, as in Fig. 2, and between said sides is secured the perforated band *e*, also of said sheet metal, which constitutes the face of the wheel, said band being set somewhat removed from the peripheries of the sides *c*, in order that it may not come in contact with the ground, and thereby have its perforations filled with dirt.

A suitable door, *b*, is provided in one of the sides *c*, through which the wheel is supplied with marking material—such as plaster-of-paris or other similar suitable white powdered substance—said door being arranged to slide in the ordinary way for opening and closing.

The peripheries of the sides *c* of the wheel are made preferably serrated, in order to cause them to have a more positive engagement with the ground when rolled over the latter, whereby

the rotations of the wheel are proportionate to the distance which it is moved for measuring purposes, as hereinafter described; but said peripheries may, if desired, be made plain, as in Fig. 2. The wheel A is made preferably of such diameter that its circumference shall measure a certain number of feet—as, for instance, two or three feet, the latter being pref-

erable, owing to the convenience of measuring off, while using the wheel as a marker, the court-lines of seventy-eight, thirty-six, forty-two, and twenty-seven feet—and in order that the operator may easily count the revolutions of the wheel the radial line *h* is provided on one or both sides thereof. The wheel A is hung to rotate between the arms *o o* of the forked piece *o'*, the latter being suitably secured in the handle K. A pivot-bolt, *v*, passes centrally through wheel A and the heads of said arms *o*.

To provide convenient means for pressing the marking material which drops from the wheel against the ground, and thereby guard against its easy displacement, the drag *d*, of iron or other heavy substance, is provided, to be drawn immediately after the wheel A as the latter rolls along and leaves said material. Said drag *d* is hung by a pivot-pin, *n*, in each end to the arm *w*, one on each side of wheel A, said arms being loosely hung on the bolt *v*, so that nothing shall prevent the drag *d* from resting with its whole weight on the ground.

To provide means for lifting the said drag off from the ground, if desired, while the wheel A is being operated, and to insure the proper position of the drag under the handle, as shown, the arm *x*, having the pin *z* therein, which engages with the arm *o* of the fork-piece *o'*, is applied to each of said arms *w* on either side of wheel A.

In view of the foregoing detailed description of the marker, the operation will be easily understood, it being requisite only to supply the hollow wheel A with the aforesaid powdered marking material, roll it on the court-lines, meanwhile noting the revolutions of the wheel, whereby the length of the lines marked is determined.

It is obvious that the marker may be made, if desired, without the drag *d* and its supporting-arms.

What I claim as my invention is—

1. A tennis-court marker consisting of a hollow wheel having a perforated face and sides, one of which is provided with a suitable door, substantially as described, whose peripheries extend beyond said perforated face to prevent the contact of the latter with the ground, and a handle having bifurcated arms, between which said wheel is hung to rotate,

combined and operating substantially as described.

2. A tennis-court marker consisting of a hollow wheel having a perforated face and 5 sides, one of which is provided with a suitable door, substantially as described, whose peripheries extend beyond said face and are serrated, and a handle having bifurcated arms, between which said wheel is hung to rotate, 10 combined and operating substantially as set forth.

3. A tennis-court marker and measurer consisting of a hollow wheel, substantially as described, having a perforated face and a given 15 circumference, and the radial line *h* thereon, extending between its axis and its periphery, and a handle having bifurcated arms, between which said wheel is hung to rotate, combined and operating substantially as set forth.

4. A tennis-court marker consisting of a 20 hollow wheel, substantially as described, having a perforated face, and a suitable door, through which to supply marking material to the wheel, a handle having the bifurcated arms *o*, a bolt passing through the ends of 25 the latter and said wheel, on which the latter rotates, an arm, *w*, having the arm *x* thereon, pivoted on said bolt on each side of the wheel and engaging with said arms *o*, and the drag *d*, pivoted between said arms *w*, and adapted to 30 rest on the ground near said wheel, combined and operating substantially as set forth.

JAMES H. BULLARD.
